(57) **CLAIM**

The ornamental design for a scale, as shown and described.

DESCRIPTION

FIG. 1 is a top, front, left side perspective view of a scale showing my new design;

FIG. 2 is a top plan view thereof;

FIG. 3 is a front elevational view thereof;

FIG. 4 is a rear elevational view thereof;

FIG. 5 is a left side elevational view thereof, the right side elevational view being a mirror image;

FIG. 6 is a top plan view of a modified embodiment thereof;

FIG. 7 is a front elevational view thereof;

FIG. 8 is rear elevational view thereof; and,

FIG. 9 is a left side elevational view thereof, the right side elevational view being a mirror image.

The bottoms are unornamented and are not shown.
